SEWING-MACHINE FOR FINISHING BUTTONHOLES.

987,966.

Specification of Letters Patent. Patented Mar. 28, 1911.

Application filed May 5, 1910. Serial No. 559,630.

To all whom it may concern:

Be it known that we, CHARLES A. DAHL, a citizen of the United States, and resident of Roxbury, county of Suffolk, State of Massachusetts, and whose post-office address is No. 16 Copeland street, Roxbury, Massachusetts, and CHRISTIAN H. T. HAGELSTEIN, a citizen of the United States, and resident of Dorchester, county of Suffolk, State of Massachusetts, and whose post-office address is No. 117 Park street, Dorchester, Massachusetts, have invented an Improvement in Sewing-Machines for Finishing Buttonholes, of which the following description, in connection with the accompanying drawing, is a specification, like characters on the drawing representing like parts.

This invention has for its object the production of a sewing-machine for finishing buttonholes, of the type wherein the work is bent so that the needle may enter and its point emerge from the same side of the work to produce a blind stitch, such machines being particularly adapted for finishing buttonhole pieces for boots and shoes.

In sewing machines of the type referred to the work is intermittently engaged and bent by a vibrating bender, and the eye-pointed needle is reciprocated longitudinally to enter and be withdrawn from the bend formed in the work, a lateral vibration being given to said needle on alternate thrusts in order to effect the formation of the desired stitching which holds down the thrum-ends and the stay-cord, if used.

We have so constructed and arranged the various mechanisms in our present invention that the machine can be run at a high speed without interfering with the certainty and accuracy of the several mechanisms embodied therein, the motions of the different moving parts being perfectly smooth and requiring a relatively small expenditure of power for the machine as a whole.

It is well known that high speed in a machine tends to increase vibration or chattering of certain rapidly moving parts, with resultant loss in accuracy, and herein we have guarded against such objectionable features by structural arrangements of such character that such vibrational or chattering action is practically eliminated.

Among the various novel features of our

invention, to be hereinafter described in detail, one of the most important is the bender-carrier and its general construction and operation, whereby a positive, direct and smooth reciprocation is imparted to the bender so that the work will be bent accurately and effectively.

Another feature of importance is the needle-guide and the means whereby it is supported so that it shall always be presented at the proper instant and in the correct position for coöperation with the needle.

Herein we employ, in coöperation with the reciprocating needle, an oscillating shuttle, and the reciprocation of such needle and the oscillation of the shuttle are effected from a common actuator, whereby said parts of the stitch-forming mechanism are always maintained in exact and proper relationship.

The various novel features of our invention will be fully described in the subjoined specification and particularly pointed out in the following claims.

Figure 1 is a top plan view of a sewing-machine for finishing buttonholes, embodying our present invention, the cover-plate and throat-plate being omitted, and with the bender-carrier and presser-foot carrier broken off to show the parts of the mechanism which would otherwise be hidden; Fig. 2 is a longitudinal section of the machine taken on the line 2—2, Fig. 1; Fig. 3 is a transverse sectional detail of the bender-actuating cam and the adjacent part of the bender-carrier, taken on the line 3—3, Fig. 2, looking toward the right; Fig. 4 is a transverse section through the main frame on line 4—4, Fig. 1, but showing in elevation the needle-reciprocating mechanism, the connection between it and the shuttle to oscillate the latter, and the four-motion feed mechanism, a portion of the work being shown in section on the throat-plate and bent for the reception of the needle; Fig. 5 is a detail view in side elevation of the feed mechanism, the parts being shown in the position assumed at the end of the feed of the work; Figs. 6 and 7 are details in side elevation of a portion of the feed mechanism, in successive positions intermediate the positions of such portion as illustrated in Figs. 4 and 5; Figs. 8 and 9 are

separate views in side elevation of the yoke-like followers which coöperate with the actuating cams of the feed mechanism; Fig. 10 is a top plan view of the throat-plate; Fig. 5 11 is a perspective view of the needle-guide and its elongated cylindrical shank; Fig. 12 is a view of the feed-cams which govern the operation of the mechanism for feeding the work, the main shaft being shown in 10 cross-section.

In our present invention the eye-pointed needle is reciprocated longitudinally to enter transversely the bend formed intermittently in the work, and as the needle path is parallel to the feed of the work said needle is vibrated or moved laterally in opposite directions at each alternate thrust, the reciprocation and lateral vibration of the needle being substantially the same as in United 20 States Patent No. 404,863 granted June 11, 1889 to John Reece, but the mechanism for effecting such needle movements are essentially different from the means shown in said patent. While the four-motion type 25 of feed mechanism herein employed is broadly old and well known certain structural details thereof are novel, so far as we are aware, and coöperate with other parts of the mechanism as a whole in increasing the 30 speed of operation of the machine.

The bed-plate 1, Figs. 1, 2 and 4, is of suitable size and shape to sustain the operating parts of the machine, the top of said bed-plate having an elongated opening 2 35 therein for the reception of a suitable cover-plate, not shown, and opposite seats 3, 3 near the front end of such opening receive the throat-plate, to be referred to. The main or driving shaft 4 extended longitudinally beneath the bed-plate and supported 40 in suitable bearings 5, 6 and 7, Figs. 1 and 2 is provided with a clutch device of any suitable character and including a band-pulley 8, the operation of the clutch being controlled by an arm 9 fixedly attached to a short rock-shaft 10 mounted in suitable bearings beneath the bed-plate, the clutch device herein illustrated being substantially such as forms the subject-matter of United States 50 Patent to Reece, No. 367,063, dated July 26, 1887. As such clutch device is not of our invention further description thereof is unnecessary beyond the statement that the pulley 8 runs loose on the shaft 4 except when 55 the clutch is set in operation by elevation of the forward end of the arm 9. The rock-shaft 10 is returned to normal position by means of a spring 11 acting upon an arm 12 fast on the rock-shaft, to thereby open or 60 render inoperative the clutch and stop rotation of the driving shaft 4. A hub 13 loose on the rock-shaft has a rearwardly extended starting arm 14, Fig. 1, provided with an adjustable screw-stud 15 which bears upon the 65 upper face of a tail 16 rearwardly extended

from the hub of the clutch-controlling arm 9, so that when the arm 14 is pulled down, as by a link 17 operated by a foot-treadle, (not shown) the controlling arm 9 will be swung upward to set the clutch. Said hub 13 is 70 provided with a short upturned and forwardly extended arm 18 yieldingly connected by springs 19 with a long arm 20 having its hub 21 fulcrumed on the rock-shaft 10 between the bearing for the latter and the hub 13 mounted on the shaft, said arm 20 being located at one end of the base on which the bed-plate 1 is carried, and below the bed-plate. When the starting arm 14 is depressed the arm 18 acts through the springs 80 19 to swing upward the arm 20, the front end of which carries an upright, adjustable stud 22 provided with a check-nut 23, Fig. 2.

Referring now to Figs. 1 and 2, a heavy horizontal and rather long rock-shaft 24 is 85 mounted at right angles to and above the driving shaft 4, in suitable bearings 25 beneath the bed-plate and forms a fulcrum for the hub 26 of a presser-foot carrier, shown as a curved arm 27 overhanging the bed-plate and rising through an opening 1* therein above the rock-shaft 24, the said carrier 27 having an extension 28 projecting from its hub above the bed-plate toward the right-hand side of the machine, Figs. 1 and 2, and provided with an enlargement 29 with which the stud 22 coöperates. When said stud is raised by the action of the starting arm 14 the extension 28 rocks the hub 26 and thereby depresses the free end of the overhanging presser-foot carrier 27, as will be apparent, such free end of the carrier being shaped to present lateral ears 30 which provide bearings for the usual bar 31 of a presser-foot 32, Figs. 2 and 4, the presser-foot being held down upon the work by a spring 33 acting upon a collar 34 fast on the bar 31, as shown in Fig. 4. The extension 28 is held against the stud 22 and also pulled down to lift the presser-foot carrier 27 by a spring 35, shown only in the plan view, Fig. 1, attached at its lower end to the bed-plate and at its upper end to a pin 36 on the carrier-extension 28, the spring acting automatically to lift the presser-foot from the 100 work when the operator releases the starting arm 14. We have provided adjustable means to limit the downward swing of the carrier 27, said means comprising a headed 105 stop-screw 37 the shank of which passes through a hole in a horizontal ear 38 on the extension 28 and through the bed-plate into a suitable depending and threaded socket 39 beneath the bed-plate, a set-screw 40 holding the stop-screw in adjusted position, Fig. 2. 110 This adjustment of the downward swing of the carrier enables us to accommodate work of various thicknesses very accurately, the presser-foot 32 accommodating itself to slight variations in thickness of any given 115 120 125 130

piece of work and to the movements of the usual toothed feed-bar through its spring 33. In our present invention the bender-carrier is made substantially C-shaped, the upper 5 and lower links 41, 42 thereof being formed integral with each other and with a strong hub 43 which is secured by set-screw 44 on the rock-shaft 24, the lower limb 42 being located wholly beneath the bed-plate, see Fig. 10 2, and extending toward the stitch-forming mechanism at the left-hand side of the machine, the extremity of said limb having a lateral, flattened foot 45, Fig. 3, which serves as a follower for the bender-actuating cam 15 46, a spring 47, Fig. 2, connecting the bottom of the bed-plate, and the limb 42 maintaining the follower in engagement with said cam.

As shown in Fig. 3 the cam has a long 20 dwell portion 46* to maintain the bender depressed upon the work during the penetration of the latter by the needle, the balance of the cam being shaped to impart a rapid oscillation to the bender-carrier between the 25 periods of rest during which the needle enters and leaves the work. The free end of the upper limb 41 (which latter rises through the opening 1* in the bed-plate) is shaped to present an upright and elongated 30 split hub or clamp 48 which receives the shank 49 of the bender 50, the shank being held securely in the clamp by suitable clamping-screws 51. The bender 50 is practically a prolongation of the shank, and tapered at 35 its front and rear sides toward its lower extremity, which is transversely convexed, as shown in Fig. 4, to avoid injury to the work, the width of the blade-like tip of the bender being shown in Fig. 2, the bender in practice reciprocating in substantially vertical plane at right angles to the line of feed of the work. The presser-foot 32 is cut away 40 adjacent the tip of the bender to effectually clear it and prevent any interference with 45 the operation thereof, said bender acting upon the work adjacent to and at one side of the usual serrated or toothed feed-bar 52 supported and actuated by mechanism to be referred to hereinafter.

50. The throat-plate 53, shown separately in Fig. 10, fits into the seats 3, 3 in the bed-plate and is slotted at 54 for the feed-bar 52, said throat-plate having a deep groove 55 therein adjacent and at right angles to the slot, into which groove the work is bent or pressed intermittently by the bender 50, the groove being formed in a depending thickened portion 56 of the throat-plate provided with a flattened needle-passage 57 which intersects the walls of the groove. A circular hole 58 in the bottom of the groove directly beneath the needle path traverses the depending part 56 of the throat-plate, the latter being quite thin, but the described thickening thereof provides ample depth for the work-

receiving groove and needle passage and not only strengthens the plate very greatly but also supports it at the point subjected to greatest strain, for the bottom of the thickened part 56 rests upon a part 59 of the 70 shuttle-case. The reciprocating bender 50 and the grooved portion of the throat-plate coöperate to form the bend in the work preparatory to the entrance of the needle thereto, and by mounting and actuating the 75 bender as herein shown we get a very direct, powerful and smooth motion, which can be speeded up to a high rate, say from 1600 to 2000 stitches per minute. The bender and bender-carrier operate as a unit and the motion of the cam 46 is transmitted directly to the bender through the bender-carrier, the shape of the latter above the bed-plate affording ample room for the manipulation 80 of the work, as the limb 41 is very similar in 85 shape to and is located beside the presser-foot carrier 27. In fact these two carrier members and the extension 28, with the presser-foot and the bender, are substantially the only parts of the mechanism 90 exposed above the bed-plate of the machine.

The part 59 of the shuttle-case is vertically drilled in alignment with the hole 58 in the throat-plate, to form an elongated and rigid bearing for a long cylindrical shank 95 60, best shown in Fig. 2, which is shaped at its upper end to form the needle-guide 61 having its upper face 62 slightly beveled, as shown in Figs. 4 and 11. This needle-guide is raised and lowered at suitable intervals, and when raised, its beveled face is just beneath the needle as it is moving forward to penetrate the bend in the work, to overcome any tendency on the part of the needle to be deflected downward from its proper path as its point is about to enter the work. After the needle has entered the work, and while it is completing its longitudinal movement, the guide is moved away from the needle path by a retracting spring 63 surrounding the shank 60 between the bottom of the shuttle-case extension 59 and the foot of a bracket 64 clamped on the shank, said bracket sliding upon the vertical face of the extension 59 when the needle-guide is operated. The out-turned head 65 of the bracket carries an adjustable screw-stud 66 which rests upon a rocking follower 67 having a fixed fulcrum 68 and coöperating with the cam periphery of a disk 69 fast on the driving shaft 4, the screw-stud 66 providing for accurate adjustment of the needle-guide. Said disk has a wrist-pin 70 connected by a link 71 with a cross-head 72 longitudinally 100 slidable on a horizontal guide-rod 73 fixed in the base of the main frame adjacent the stitch-forming mechanism, the rotation of disk 69 reciprocating the cross-head in parallelism with the direction of feed of the work. Depending from the cross-head is a 110

115

120

125

130

stud 74, Fig. 4, on which is pivotally mounted the rear end of a link 75, the front end of the latter embracing a pivot-stud 76 eccentrically mounted on and depending from a horizontally swinging fork 77 fulcrumed on a stud 78 fixed in the bottom of the shuttle-case 79 at one side of its center.

We have provided an oscillating shuttle 80, Fig. 1, of the well-known "Singer" type, 10 said shuttle resting in the shuttle-case 79 and having its central spindle 81 extended downward through the hub-like bottom of the case, as indicated in Fig. 4, wherein the shuttle itself is omitted to avoid confusion. 15 The spindle 81 has fixed to its lower end a radial arm 82 carrying a roller or other stud 83 which enters the slotted fork 77, the shuttle and its connections with said fork, and the fork itself, being well known in the art and not of our invention, but the manner of connecting the shuttle adjuncts with the means for effecting longitudinal reciprocation of the needle are new, so far as we are aware, the oscillating type of shuttle being 20 particularly adapted for high speed without the use of gearing or similar devices.

A yoke 84 is provided with bearings 85 to loosely embrace and rock upon the guide-rod 73, longitudinal movement of the yoke 30 being prevented by a pin 86, Fig. 4, driven through one of said bearings and entering an annular groove 87 in the guide-rod. Said yoke sustains the horizontal and longitudinally reciprocating needle-bar 88 to 35 which is secured the eye-pointed needle 89, substantially as in the Reece Patent No. 404,863 previously referred to, and by means of a switch-cam 90 on the main shaft 4, rocker 91 and link 92 the said yoke and 40 needle-bar are vibrated laterally, as in said patent, the link being adjustably connected with a slotted arm 93 depending from the yoke.

The work is fed in the direction of the 45 longitudinal reciprocation of the needle, as in the Reece patent above mentioned, and each descent of the bender 50 acts upon the work W, Fig. 4, to form a bend therein in the groove 55 of the throat-plate, and as the 50 yoke 84 is vibrated laterally the needle will penetrate and pass through the bend in the work first at one and then at the other side of the usual stay-cord, not herein shown, its 55 delivery to the work being common in the art and the means for such delivery of the cord form no part of our invention. At each forward stroke of the needle the needle-guide 61 rises to guide the needle at the instant its point engages and penetrates the 60 bend formed in the work, as will be understood.

The use of a needle-guide in machines of this type is old, broadly, but the construction of the guide with an elongated shank or 65 body portion, supported by and vertically

movable in a long and rigid bearing, as herein provided, insures a smooth and steady motion for the guide, absolutely necessary when the machine is run at high speed, for there is then no chance for the 70 guide to chatter or vibrate laterally either when in operative position or during its movement toward and from such position. As shown in Fig. 2 the upper face of the 75 needle-guide is made wide enough to coöperate properly with the needle irrespective of the lateral change in its path on alternate forward strokes.

Referring to Fig. 4 it will be seen that the cross-head 72 is reciprocated on the guide-rod 73 between the bearings 85 of the needle-bar yoke 84, without interference therewith, said cross-head being positively connected with the needle-bar, as will now be described, to effect the longitudinal reciprocation thereof. A laterally extended collar 94 fast on the needle-bar is pivotally connected with one end of a short link 95, the other end of said link being pivotally connected with the free end of a long, horizontally swinging arm or transmitter 96 fulcrumed at 97 on the underside of the bed-plate 1, a second link 98 pivotally connected with transmitter at 99 extending rearward and being pivotally connected at 100 with a boss 101 95 on the cross-head. As the main shaft 4 revolves at high speed the cross-head is rapidly reciprocated by the link 71, and through link 75 the shuttle 80 is oscillated at the requisite rate of speed to coöperate 100 properly with the needle, and as the cross-head reciprocates it swings the transmitter 96 about its fulcrum 97, such swinging movement of the transmitter effecting longitudinal reciprocation of the needle-bar 88 105 by the short link 95, but with a stroke slightly longer than that of the cross-head, in order to coöperate properly with the shuttle. Thus the cross-head is the common actuator for the oscillating shuttle and for 110 the longitudinally reciprocating needle, and when the latter is vibrated laterally on alternate thrusts the link 95 accommodates itself thereto by a slight lateral swinging movement about its pivotal connection with the 115 transmitter 96. In actual practice this lateral movement of the needle-bar is so slight that no special means is required to take care of it, it being remembered that as the needle-bar reciprocates in the yoke 84 there 120 can be a small relative angular movement between such parts as the yoke is vibrated. The connection between the cross-head 72 and the needle-bar gives a rapid reciprocatory movement to the latter with smooth 125 action irrespective of the speed at which the machine is run, and as the needle and shuttle are driven from the same prime mover or actuator by direct and positive connections the two stitch-forming members will always 130

be in proper timing with relation to each other.

By reference to Fig. 2 it will be seen that the fulcrum 97 for the transmitter 96 is made quite long and of relatively large diameter, to not only minimize wear but also to provide a firm support or bearing upon which the transmitter rocks and thereby prevent any tendency of the transmitter to swing out of true. It is important that the transmitter swing in a fixed path, not only for the smooth operation of the parts connected therewith but also because the transmitter acts through the link 98 and its pivotal connections to obviate any tendency of the cross-head to turn upon the guide-rod 73 as it is reciprocated thereupon.

Referring to Fig. 1 the needle-thread t_1 leads from a suitable source of supply through a guide t_2 to a tension device t_3 and thence through an eye in a take-up lever t_4 vibrated by a suitable cam t_5 on the main shaft, said thread passing from the take-up lever to and around a guide t_6 on the yoke 84 and about a pin t_7 also on the yoke, and then to the eye of the needle 89, the thread-guiding and controlling devices being of any suitable or usual construction and not of our invention.

Referring now to the feed-motion for the work, the feed-bar 52 has fixedly attached to it a yoke-like follower 102, shown separately in Fig. 8, which embraces and cooperates with one of the feed-cams, as 103 fast on the main shaft 4, while the yoke-like follower 104, shown separately in Fig. 9, cooperates with the other feed-cam 105 fast on the main shaft, adjacent to or forming a part of the cam 103, said cams being shown more clearly in Fig. 12, which illustrates them in the position shown in Fig. 5. Cam 103 acts through its follower to elevate the feed-bar 52, as in Figs. 5 and 7, and to depress it as in Figs. 4 and 6, and the cam 105 acts through its follower to effect the fore and aft motion of the feed-bar. During the quarter revolution of the main shaft from the position shown in Fig. 4 to that shown in Fig. 6 the feed-bar is maintained depressed by cam 103 and it is moved to the right, by cam 105, and on the next quarter revolution to the position shown in Fig. 7 the cam 103 operates to elevate the feed-bar into position to engage and effect the next feed movement of the work to the left, viewing Fig. 4, or toward the back of the machine, cam 105 not acting during such quarter-revolution. On the third quarter-revolution, however, the termination of which is shown in Fig. 5, the cam 105 operates to effect the feed stroke of the feed-bar toward the back of the machine, while cam 103 merely operates to maintain said feed-bar elevated. The final quarter-revolution of the main shaft from the position shown in

Fig. 5 to that shown in Fig. 4 completes the feed cycle, cam 103 lowering the feed-bar away from the work while cam 105 is inactive so far as movement of the feed-bar is concerned. This cycle, broadly considered, is the familiar four-motion feed well known in the sewing-machine art, but the mechanism devised by us is novel in its particular structure and arrangement, so far as we are aware.

The follower 104 is fulcrumed on stud 106 on the main shaft bearing 5 and its lower portion is pivotally connected at 107 to a link 108 extended toward the back of the machine and pivotally connected at 109 to the lever arm 110 fulcrumed at 111 to an ear 112 of the main frame. Said lever arm has an upturned, slotted extension 113, clearly shown in Fig. 5, in which is adjustably mounted a stud 114 on which is pivoted a frontwardly extended link 115 pivotally attached at 116 to a suitable ear on the upper part of the follower 102. The follower 102 can rise and fall in accordance with the position of its controlling cam 103 whether the lever 110 and its extension 113 is in the position shown in Fig. 4 or in the position shown in Fig. 5, and the fore and aft movement of the feed-bar 52 is effected by cam 105 acting to swing its follower 104 on its fixed fulcrum 106. Such swinging movement of the follower is transmitted by link 108 to the lever 110 and its extension 113, and from the latter through link 115 to follower 102, and as the latter is thereby moved bodily forward or backward the attached feed-bar moves with it. The length of the feed-stroke is regulated by the stud 114, adjustment of the latter toward or from the fixed fulcrum-stud 111 decreasing or increasing, respectively, the stroke of the feed-bar 52.

It will be observed that every movement of the feed-bar is effected positively and it is at all times under the control of one or the other of the actuating cams, lost-motion being practically eliminated, and all moving parts are so constructed and arranged that the operation of the feed mechanism will not vary in its precision or accuracy irrespective of the rate of speed at which the machine is run.

The operation of the machine as a whole will be readily understood from the foregoing description, taken in connection with the drawings, the bender intermittently engaging and forming a transverse bend in the work prior to each thrust of the needle, the latter being longitudinally reciprocated in proper timing with relation to the oscillations of the shuttle, and said needle is vibrated laterally on alternate thrusts. The bender-carrier and bender move as a unit, and the bender-carrier is provided with a long, heavy hub which rocks on the shaft 24

as a fulcrum, said shaft being so mounted as to eliminate shaking or chattering when the apparatus is running at high speed, thereby insuring an exact and smooth operation of the bender with reference to the parts of the stitch-forming mechanism, and with a direct, positive transmission of power from the bender-actuating cam through the bender-carrier to the rigidly attached 10 bender.

The bed-plate of the machine is smooth and unobstructed between the bender and the base of the upper, overhanging limb of the bender-carrier, so that ample space is 15 provided for the manipulation of the work without any obstruction.

The various adjustments for the bender, needle-guide, stitch-forming devices, and feed-motion are all located at the stitch-forming side of the machine, and can be 20 readily set by the operator as occasion demands.

Changes or modifications in various details of construction and arrangement may 25 be made by those skilled in the art without departing from the spirit and scope of our invention as set forth in the claims annexed hereto.

Having fully described our invention, 30 what we claim as new and desire to secure by Letters Patent is:

1. In a sewing-machine, means to form bends in the work, stitch-forming mechanism, including a horizontally-reciprocating needle-bar having an attached eye-pointed needle to penetrate the bends formed in the work on each forward stroke, a laterally vibrated support for the needle-bar, and a shuttle to coöperate with the needle, combined with an actuating member reciprocated in a fixed path, operating connected between said member and the shuttle, to oscillate the latter, a swinging transmitter operatively connected with said actuating member, and positive connections between the transmitter and the needle-bar, to effect horizontal reciprocation thereof while permitting lateral vibration of the needle-bar support.
2. In a sewing-machine, means to form bends in the work, stitch-forming mechanism, including a horizontally-reciprocating and laterally-vibrating, eye-pointed needle to penetrate the bends formed in the work on each forward stroke, and a shuttle to coöperate with the needle, combined with an actuating member reciprocated in a fixed path, connections between said member and the shuttle to oscillate the latter, a horizontally swinging transmitter, a link connecting it and said actuating member, to swing it, and connections between the transmitter and the needle to effect horizontal reciprocation thereof while permitting lateral vibrational movement of the needle.
3. In a sewing-machine, means to form bends in the work, stitch-forming mechanism, including a horizontally-reciprocating needle-bar having an attached eye-pointed needle to penetrate the bends formed in the work, a laterally-vibrated yoke in which the needle-bar reciprocates, and an oscillating shuttle, combined with a fixed guide-rod parallel to the needle path, and on which said yoke rocks, a cross-head reciprocated on 75 said guide-rod, adjustable connections between the cross-head and shuttle to oscillate the latter, and separate, positive connections between said cross-head and the needle-bar to reciprocate the needle-bar in the yoke, 80 such connections permitting lateral vibration of the yoke.
4. In a sewing-machine, means to form bends in the work, stitch-forming mechanism, including a horizontally-reciprocating 85 needle-bar having an attached eye-pointed needle to penetrate the bends formed in the work on each forward stroke, a laterally vibrated support for the needle-bar, and an oscillating shuttle, combined with a cross-head reciprocated in a fixed path, means, including a link and a horizontally swinging arm, interposed between said cross-head and shuttle, to oscillate the latter, an elongated transmitter fulcrumed to swing in a horizontal path above the cross-head, a link 90 connecting the latter and said transmitter, a laterally extended collar on the needle-bar, and a link pivotally connected with said collar and transmitter, to effect horizontal reciprocation of the needle-bar while permitting 95 lateral vibrational movement thereof.
5. In a sewing-machine, means to form bends in the work, stitch-forming mechanism, including a horizontally-reciprocating 100 needle-bar having an attached eye-pointed needle to penetrate the bends formed in the work on each forward stroke, means to effect lateral vibration of the needle-bar on alternate forward strokes, and an oscillating shuttle to coöperate with the needle, combined with an actuating member reciprocated in a fixed path below and parallel to the path of movement of the needle-bar, positive operating 105 connections between said member and the needle-bar to reciprocate the latter, said connections including a link laterally movable to accommodate the lateral vibration of the needle-bar, and independent and direct-acting 110 connections between the actuating member and the shuttle to oscillate the latter.
6. In a sewing-machine, means to form bends in the work, stitch-forming mechanism, including a horizontally-reciprocating 115 needle adapted to penetrate the bend in the work on each forward stroke, and a complementary stitch-forming member to coöperate with the needle, a vertically-movable needle-guide having an elongated shank, a fixed tubular bearing in which said shank 120
- 125
- 130

is slidale longitudinally, and means to move said needle-guide in its bearing into operative engagement with the needle as its point is about to enter the bend formed in the work.

5. In a sewing-machine, means to form bends in the work, stitch-forming mechanism, including an eye-pointed needle adapted to penetrate the bend in the work on each 10 forward stroke, and means to reciprocate it, a needle-guide having an elongated cylindrical shank, a fixed tubular bearing for and in which the shank is movable longitudinally toward and from the needle path, a 15 spring to retract the needle-guide, and positively-acting means connected with the shank beyond the bearing, to move the guide into operative engagement with the needle at a predetermined point in the forward stroke 20 thereof before it enters the bend in the work, the retracting spring for the needle guide being interposed between the connection with its operating means and the bearing.
25. In a sewing-machine, a throat-plate having a depending thickened portion provided with a groove and with an intersecting vertical hole, stitch-forming mechanism, including a needle horizontally reciprocated 30 across the groove and above the hole in said thickened part of the throat-plate, a bender to bend the work intermittently into said groove to be penetrated by the needle on its forward stroke, a needle-guide having an 35 elongated shank snugly fitting and longitudinally movable in the hole in the thickened portion of the throat-plate and laterally supported thereby against sidewise vibration, said shank being extended below the thick- 40 ened portion of the throat-plate, means connected with the lower end of the shank to move it and said needle-guide in a straight path to bring said guide into operative engagement with the needle as its point is 45 about to enter the bend formed in the work, and a fixed lateral bearing for said shank co-operating therewith between the thickened portion of the throat-plate and the operating means connected with the lower 50 end of the shank.
9. In a sewing-machine, a throat-plate having a bending groove and a depending, thickened portion provided with a hole intersecting the groove, a fixed part of the 55 machine having a hole registering with the hole in the throat-plate, and forming therewith an elongated rigid bearing, a bender to bend the work intermittently into the groove, a horizontally-reciprocating needle 60 to cross the groove and penetrate the bend in the work, a needle-guide having an elongated shank longitudinally movable in and extended below the rigid bearing, and means connected with the lower end of said shank 65 to reciprocate it in the bearing, and move

the needle-guide into operative engagement with the needle on each forward stroke thereof.

10. In a sewing-machine, a throat-plate having a bending groove and a depending, thickened portion provided with a hole intersecting the groove, a fixed part of the machine having a hole registering with the hole in the throat-plate and forming therewith an elongated, rigid bearing, a bender 70 to bend the work intermittently into the groove, a horizontally-reciprocating needle to cross the groove and penetrate the bend in the work, a beveled needle-guide having an elongated shank longitudinally movable 75 in and projecting below the rigid bearing, a spring to retract the needle-guide, and means connected with the projecting end of its shank to elevate the same and move the needle-guide into operative engagement with 80 the needle on each forward thrust of the latter.

11. In a sewing-machine, a bed-plate having an opening therein, means to form bends intermittently in the work, including a vertically movable bender, a bender-carrier having a curved arm passing through the opening in the bed-plate and overhanging the latter, a connected curved lower arm beneath the bed-plate, and a fulcrum-shaft mounted 95 beneath the bed-plate and to which said arms are rigidly attached, the bender being clamped on the free end of said overhanging arm, and an actuating cam co-operating directly with said lower arm to oscillate the 100 bender-carrier.

12. In a sewing-machine, a bed-plate having an opening therein, means to form temporary and intermittently depending bends in the work, said means including a C-shaped bender-carrier fulcrumed below the bed-plate, the upper limb of said bender-carrier passing through the opening in the bed-plate and having its free end overhanging the bend-forming point, an upright clamp on the free end of said limb to fixedly hold the bender substantially at right angles to the bed-plate, the bender depending from the clamp, and an actuating cam co-operating with the lower limb of the bender-carrier to 110 oscillate the same and effect reciprocation of the bender in a substantially vertical path.

13. In a sewing-machine, a bed-plate, a grooved bending member sustained thereby, a C-shaped bender-carrier fulcrumed beneath the bed-plate, and having the free end of its upper, longer limb overhanging said 115 grooved member, a vertically movable bender fixedly mounted on the free end of the said limb of the bender-carrier above and substantially at right angles to said grooved member, and an actuating cam co-operating directly with the shorter, lower limb of the bender-carrier beneath the bed-plate, to oscillate the bender-carrier and reciprocate the 120 125 130

bender toward and from the stationary bending member in a path substantially at right angles to it and the bed-plate.

14. In a sewing-machine, a bed-plate, a stationary bending member sustained thereby and having a groove, a vertically movable bender to bend the work intermittently into the groove, a C-shaped bender-carrier, an elongated fulcrum shaft therefor beneath the bed-plate parallel to the direction of feed of the work, the upper limb of the bender-carrier rising above and overhanging the bed-plate and to which limb the said bender is clamped, and an actuating cam coöperating directly with the lower limb of the bender-carrier beneath the bed-plate, to oscillate said bender-carrier.

15. In a sewing-machine, a bed-plate having depending bearings and an opening between them, an elongated rock-shaft mounted in said bearings parallel to the direction of feed of the work, a C-shaped bender-carrier having a hub fixed on the said rock-shaft between the bearings, the upper limb of said bender-carrier rising through the opening in and overhanging the bed-plate, a vertically movable bender fixedly mounted on such upper limb, the lower limb extending beneath the bed-plate, an actuating cam coöperating directly with the lower limb to oscillate the bender-carrier, and a spring to maintain the lower limb in coöperation with the cam.

16. In a sewing-machine, a bed-plate, a main driving shaft beneath it, a C-shaped bender-carrier, a rock-shaft on which it is fixed, said rock-shaft being located beneath the bed-plate at right angles to the driving shaft, the upper limb of the bender-carrier overhanging the bed-plate and having an attached bender, an actuating cam on the driving shaft coöperating directly with the lower limb of the bender-carrier, to oscillate the same, a presser-foot, a carrier therefor fulcrumed on said rock-shaft, and manually controlled means to rock said carrier to raise or lower the presser-foot.

17. In a sewing-machine, a driving shaft provided with a manually controlled clutch-device to start and stop it, a C-shaped bender-carrier having a vertically movable bender fixedly mounted on its upper limb, an actuating cam on the driving shaft coöperating directly with the lower limb of the bender-carrier to oscillate the latter, a fulcrum-shaft for said bender-carrier, a presser-foot, a carrier therefor fulcrumed on said shaft and having a lateral extension, yield-

ingly acting means to coöperate with said extension and operatively position the presser-foot when the clutch-device is set, and an adjustable stop coöperating with said extension to limit movement of the presser-foot when said yieldingly-acting means operate.

18. In a sewing-machine, stitch-forming mechanism, including a horizontally-reciprocating and laterally vibrated eye-pointed needle, intermittently operating means to form bends in the work transverse to the needle-path, to be penetrated by the needle on each forward thrust, a feed-block movable parallel to the path of the needle as it is reciprocated, two rotating feed-cams, a follower-yoke coöperating with one of said cams and fixedly connected with the feed-block, to raise and lower it, a follower-yoke coöperating with the other cam, a stationary fulcrum for said last named follower-yoke, a lever, a link connecting it and the last-named follower-yoke, a second link connecting said lever and the follower-yoke fixedly connected with the feed-block, whereby rocking of said lever imparts a fore and aft stroke to the feed-block, and a stationary fulcrum for the lever.

19. In a sewing-machine, stitch-forming mechanism, including a horizontally-reciprocating and laterally vibrated eye-pointed needle, intermittently operating means to form bends in the work transverse to the needle-path, to be penetrated by the needle on each forward thrust, and a main driving shaft to effect the actuation of the stitch-forming mechanism and the bending means, combined with a feed-block movable parallel to the path of the reciprocating needle, a follower fixedly connected with said block, a cam on the driving shaft coöperating with said follower, to raise and lower the feed-block, a second follower having a stationary fulcrum, a coöperating cam on the driving shaft, to swing said last named follower, and connections between the two followers whereby swinging movement of one imparts a fore and aft movement to the other follower and the attached feed-block.

In testimony whereof, we have signed our names to this specification, in the presence of two subscribing witnesses.
